SIGNALING SYSTEM

Free Calhoun, Chicago, Ill., assignor to Associated Electric Laboratories, Inc., Chicago, Ill., a corporation of Delaware

Application February 17, 1937, Serial No. 126,230

18 Claims. (Cl. 179—16)

The present invention relates to signaling systems and more particularly to impulse repeaters for use in automatic telephone systems.

In conventional forms of automatic telephone systems impulse repeaters of one type or another are employed in connection with inter-office trunk lines for the purpose of reducing to a minimum the number of conductors constituting the trunk line cables and for interrupting the 5 circuits of such trunk lines in accordance with electrical impulses produced by operation of impulsive means or a dialing device embodied in any substation connected to any calling subscriber's line. The impulses as thus repeated 10 comprise rapid fluctuations in the current through the trunk line conductors, the impulsive rate being determined by the dial speed of the impulsive means, and these current impulses cause the operation of control means, usually in 15 the form of line relays for selector or connector switches associated with the trunk lines.

Recent improvements in the design of line relays have given rise to the problem of improving the repeater circuits generally. These line relay improvements, designed primarily to increase the sensitivity thereof to received electrical impulses, have rendered unsatisfactory those forms of repeater circuits such, for example, as the high impedance bridge type, wherein the repeater 20 relay is, during the operation of the repeater, subjected to transient impulses which tend to produce false operation of the repeater relay. One form of repeater circuit which is well adapted to meet the requirements of highly sensitive line 25 relays is the well-known repeating coil type. The circuit of this type of repeater includes primary repeating coils connected in series with the incoming line conductors and terminating at a repeater line relay, the line relay being shunted 30 by a capacitor for by-passing voice frequency currents. These primary repeating coils are inductively coupled to secondary repeating coils connected in series with the conductors of the trunk line terminating at a distant selector or 35 connector switch, the circuit of the latter trunk line being interrupted in accordance with the transmitted impulses by means of the repeater line relay.

The satisfactory operation of any impulsive arrangement and more particularly an arrangement of the type briefly described above is measured by the ability of the device or control means to be controlled by the transmitted impulses 40 faithfully to follow the impulses created at the impulsive device and repeated over the inter-

connecting trunk lines by the impulse repeaters. If any substantial amount of distortion is introduced in the impulses in the transmission path between the impulsive device and the control means faithful response of the latter means can 5 not be obtained. Such distortion may take any one of a variety of forms. Thus, if the period of energization of the control device is greatly less than the contact make period of the impulsive means, the device may have insufficient time 10 in which fully to operate. Conversely, if the period of de-energization of the control device is substantially less than the contact break period of the impulsive means, the device may have insufficient time in which to de-energize and prepare 15 for a succeeding impulsive cycle. Again, if any one of the line relays in a chain of repeaters is falsely operated more than once during any one impulsive cycle of the impulsive means, false 20 operation of the control device may result.

In a system of the type indicated, the amount of impulse distortion is determined at least in part by the relation between the circuit constants of the line to which the dialing or impulsive device is connected, the constants of the elements 25 of the repeater associated with the line, the constants of any other apparatus associated with the line as, for example, normally inactive bridged ringers on a party line, the rate of impulsive 30 at the impulsive means, and to a lesser extent by the voltage of the operating batteries and the line constants of succeeding trunk lines and the constants of the impedance elements associated therewith. Usually the circuit constants of the individual subscribers' lines and the trunk lines 35 are fixed by the physical arrangement of the system and cannot economically be altered. The impulsive rate may have any value within a range, the range usually extending between 8 and 12 interruptions per second. It will be appreciated, therefore, that the impulsive characteristics 40 of the subscribers' lines associated with a particular group of repeaters will vary over a wide range and when the impulsive conditions inherent in a particular subscriber's line are particularly unfavorable, the impulse distortion obtained may, even with a repeater circuit of the type specified, be so great as to preclude faithful operation of the control device to be controlled by the transmitted impulses. More specifically, a 50 subscriber's line may be in a condition which is perfectly satisfactory for efficient transmission of voice currents and yet be in a condition which is extremely unfavorable to impulse transmission thereover. This usually occurs in cases where 55

the subscriber's line circuit is excessively long so that the line resistance thereof is high, or where the shunt leakage resistance between the line conductors is extremely low, or by a combination of these two factors.

Under the conditions stated, the form of distortion which occurs is manifested in a false energization and de-energization of the line relay included in the first repeater of the repeater chain, causing a false operation of this relay which is repeated through the chain of relays to the control device. As will be pointed out in detail hereinafter, the reason for such false energization is that the circuit constants of the calling subscriber's line, the elements of the first repeater, and any other apparatus associated with the calling subscriber's line are necessarily so related to each other and to the impulsive rate as incidentally to cause, in each impulse cycle, a voltage transient across the windings of the first repeater line relay during the period of the cycle when this relay is supposed to be interrupted and corresponding to the interrupted period of the calling subscriber's line circuit.

It is an object of the present invention, therefore, to provide in a system of the character described an improved repeater capable of operating in conjunction with any subscriber's line circuit having reasonable voice frequency transmission efficiency in a manner such that impulses transmitted over the line may successively be repeated with tolerable distortion.

It is a further object of the invention to provide in a signaling system an impulse repeater arrangement, comprising a plurality of tandem connected repeaters, which is capable of producing faithful response of the impulse controlled means in accordance with impulses transmitted by impulsive means through the repeaters, and in which at least one of the repeaters is adapted to be connected to any one of a number of subscribers' lines having a wide variety of impulsive characteristics.

More particularly, it is an object of the invention to provide an improved repeater of the general type described which is capable of repeating substantially without distortion impulses received over a line having highly unfavorable impulsive characteristics.

In brief, the objects as set forth above are realized in accordance with the present invention by associating with at least one of the repeaters included in the repeater chain, reactance means for altering the circuit constants of the network between the impulsive device and the control means, thereby to reduce the impulse distortion in the impulse transmission path of the network to a tolerable value. More specifically, capacitance means is included in the first repeater of the repeater chain, in shunt with the voice frequency current by-passing capacitor and so proportioned relative to the circuit constants of a line having unfavorable impulsive characteristics, the elements of the associated repeater, and any other apparatus associated therewith that the electrical transient which occurs in each impulse cycle is delayed, following the interruption of the circuit of the line over which the impulses are transmitted, and the duration of the transient is increased. As a result, and for any reasonable impulsive rate, the circuit of this line is closed, during any one impulsive cycle, before the expiration of the transient of the preceding impulsive cycle. In other words, each open circuit impulse period is ended in the normal man-

ner by closing the line circuit to energize the first repeater, before the transient of the impulse has expired. Hence, the repeater line relay is not permitted to restore at the expiration of the transient and double operation of the repeater relay during any single impulsive cycle is prevented. If desired, the delay may be achieved entirely through the action of the capacitance means shunting the voice-frequency by-pass capacitor of the first repeater. As an alternative, this capacitance means may be so proportioned that only a portion of the required delay is achieved thereby, an additional delay being obtained due to the operating inertia of the relays included in the repeater following the first repeater, such that the combined delay intervals for each impulse cycle extend well into each succeeding cycle. It is pointed out that the term "repeater" as used herein is a generic designation intended to connote any device or combination of devices for repeating impulses received over one line to a second line or to a controlled impulse responsive device directly.

The novel features believed to be characteristic of the invention are set forth with particularity in the appended claims. The invention itself, however, both as to its organization and method of operation, together with further objects and advantages thereof, will best be understood by reference to the specification taken in connection with the accompanying drawings in which Figure 1 illustrates in partially schematic form an automatic telephone system constructed and arranged in accordance with the present invention; Fig. 2 illustrates a portion of the system of Fig. 1 reduced to its simplest form; and Figs. 3 to 5, inclusive, are graphs illustrating the operating characteristics of typical installations.

Referring now more particularly to Figure 1 of the drawings, there is illustrated in partially schematic form a telephone system of the automatic type comprising a plurality of offices or exchanges, adapted to be inter-connected by trunk lines individually having associated therewith an impulse repeater for the purpose briefly described above. The system comprises four offices or exchanges indicated at 10, 11, 12, and 13, respectively, with trunk lines extending between the offices in the conventional manner so that any subscriber's line terminating at one office may selectively be connected to any other subscriber's line terminating at the same or at any of the other offices by means of the usual line, selector and connector switches. This arrangement of elements for a connection between a subscriber's line 14, comprising conductors 15 and 16, terminating at the office 1, and a subscriber's line terminating at the bank contacts of the connector switch included in the office 13 may comprise, connected in tandem, in the order named, a line switch 17, an intra-office three-conductor cable 18 including conductors 19, 20 and 21, a first selector switch 22, an impulse repeater indicated generally at 23, a two-conductor inter-office trunk cable 24 comprising conductors 25 and 26, a second selector switch 27, a second impulse repeater 28, a second two-conductor inter-office trunk cable 29 comprising the conductors 30 and 31, a third selector switch 32, a third repeater 33, a third inter-office two-conductor trunk cable 34 comprising conductors 35 and 36 and, finally, a connector switch indicated generally at 37. It will be understood that the enumerated selector switches, trunk lines, repeaters and the connector switch individually

represent a number of similar elements located in and inter-connecting the various offices. The line, selector and connector switches may be of any desired type, although preferably the line 5 switch is of the rotary type and the selector and connector switches are of the well-known Strowger type embodying a contact selector element adapted to be translated vertically and then rotated in response to the selective and repeated 10 operation of vertical and rotary control magnets, respectively. Since these switches are entirely conventional in form, they have been indicated only schematically in the drawings.

The line 14 is shown as being of the party line 15 type having a plurality of subscribers' substations connected thereto, one of which is shown in detail at 39 and another of which is shown schematically at 40. Each of these substations is of the well-known booster type embodying selective harmonic ringers. Thus, the station 39 comprises a ringer circuit including a ringer 41 and a condenser 42 connected in series across the line 14. This circuit is connected in shunt with a winding 43 of the booster transformer through the upper contact 44 of a hook switch 45, a transmitter 46, contacts 47 and 48 of impulsing means in the form of a dialing device 49, and the lower contact 50 of the hook switch 45. A receiver 51 is provided which is connected between one terminal of the transmitter 46 and the junction point between the ringer 41 and the condenser 42 through the second winding 52 of the booster transformer. Off-normal springs indicated at 53' are also provided which are adapted 30 to short circuit the transmitter 46 and receiver 51 during the transmission of impulses. It is pointed out here that the words "impulsing cycle" as used herein denote the cycle of opening the contacts 47 and 48 for a predetermined period 35 determined by the rate of impulsing to interrupt the circuit of the subscriber's line 14, and the closing of these contacts for a predetermined period, also determined by the rate of impulsing, thereby to close the circuit of the line 14.

The control means or device which, in the system shown, is to be controlled by the impulses transmitted by the impulsing means 49 comprises the connector switch 37 and, more particularly, a line relay 53 which is connected to the trunk conductors 35 and 36 when this particular connector switch is seized. The relay 53, as is well known, controls, through a system of interconnected relays, the operation of the vertical and rotary stepping magnets of the connector to cause the selector element to select the proper set of bank contacts leading to the called subscriber's line. Since the manner of connecting such relays and their mode of operation is well known, they have been omitted from the system in order to simplify the drawings.

Each of the repeaters 23, 27 and 33 included in the transmission path between the subscriber's line 14 and the connector switch 37 is preferably of the well-known repeating coil type with the exception of the repeater 23 which is modified by the addition of means for reducing to a tolerable value distortion of the impulses in the manner described in detail hereinafter. For this reason, the repeater 23 only, has been shown in detail. It comprises the usual repeating coil transformer 56, including primary windings 57 and 58 and secondary windings 59 and 60 serially connected, respectively, in the cable conductors extending from the selector switch 22 and the cable conductors 25 and 26 comprising the trunk line 24.

The windings 57 and 58 are connected in series with the windings of a repeater line relay 70 through the contacts 81 and 82 of a battery reversing shunt relay 80. A capacitor 63 is provided in shunt with the windings of the relay 70 for by-passing voice-frequency currents around these windings and additional capacitance means comprising the capacitor 64 shunting the windings of the relay 70 is also provided for reducing impulse distortion to a tolerable value in the 10 manner to be described in detail hereinafter. Also shunting the upper winding of the relay 70, during the circuit interruption period of each impulse cycle, is a priming resistor 65 which functions partially to energize the relay 70 and 15 to render it more sensitive to received impulses. In order to repeat these impulses over the trunk line 24 the relay 70 is provided with a front armature 71 and associated contact 72 which are inserted in the conductor 26. The relay 70 is 20 also provided with an armature 73 and associated contacts 74 and 75 for controlling a slow-to-release relay 90 and for removing the resistor 65 from in shunt with the windings of the relay 70 during the closed circuit period of each impulse 25 cycle. One of the windings of the shunt relay 80 is connected in series with the secondary windings 60 across the trunk line conductors 25 and 26 and is shunted by a voice-frequency by-pass condenser 66. The other winding of the 30 relay 80 is adapted to be energized from the common battery at the contact 91 of the slow-to-release relay 90, so that when the called subscriber lifts his receiver the relay 80 becomes fully energized to operate its battery reversing 35 armatures and contacts 83-86, inclusive in the usual manner.

The slow-to-release relay 90 is also provided with contacts 92 and 93 and an armature 94 for removing negative battery from the guarding 40 conductor 19' when the relay is operated and for substituting guarding ground. An additional armature 95 and associated contact 96 are included in this relay which are connected in the circuit of the resistor 65.

Neglecting for the present the additional capacitance means 64 and its function, the system as generally described above is entirely conventional in form and its operation is well understood in the art. In brief, a call from the subscriber's substation 39 to a subscriber's line terminating in the bank contacts of the connector switch 37 is initiated by lifting the receiver at the substation 39 to operate the hook switch 45 and close the contacts at 44 and 50, thereby causing 55 the line switch 17 to select in the usual manner an idle first selector switch, as, for example, the first selector switch 22. This operation also places ground on the control conductor 19 in the usual manner, which ground extends over this 60 conductor by way of the line switch contacts to the associated connector bank contact to busy the line 14 and thereby prevent its being seized due to an incoming call thereto. In response to successive operations of the impulsing means 65 or dialing device, the selector switches 22, 27 and 32 are successively operated in the usual manner individually and successively to select idle trunks as, for example, the trunk lines 24, 29, and 34, extending between the offices 1, 2, 3, and 4. During these dialing operations, contacts 47 and 48 are periodically opened and closed to send electrical impulses over the line 14, which impulses are repeated over the trunk circuits by the repeaters 23, 28 and 33. Thus, at the conclusion 75

of the operation of the first selector 22 to select the idle trunk 19 in response to the dialing of the first digit, the contacts 47 and 48 are closed to energize the repeater line relay 70 over an obvious circuit and thereby to condition the repeater 23 to repeat the impulses of the second digit to the second selector switch 21. The operation of the relay 70 causes the operation of the slow-to-release relay 80 over the circuit 10 tending from ground at the armature 78, the contact 74, the winding of relay 80 to battery, and also closes the circuit of the trunk line 24 at the contact 72. When the slow-to-release relay 80 operates, it places guarding ground on the conductor 19' at contact 92, completes the circuit for partially energizing the relay 80 at contact 91 and prepares the circuit for the shunt priming resistor 65 at contact 96. The circuit of the priming resistor 65 is held open during the period 20 when the contacts 47 and 48 are closed by the relay 70 at back contact 75. It is pointed out that the windings of shunt relay 80 are so poled relative to each other that during the calling operation the fluxes thereof are additive and the 25 relay remains de-energized. However, when a call is completed and the called party lifts his receiver, the current through the winding in series with the repeater coils 59 and 60 is reversed, causing the relay to operate, thereby to reverse the polarity of potential applied to conductors 15 and 16 at the armatures 84 and 86. At this stage 30 of the operation and when the contacts 47 are opened for the first time during the dialing of the second digit, the line relay 70 is deenergized to open at contact 71 the circuit of the trunk line 24 and to open the circuit for the slow-to-release relay 80 at contact 74. The latter relay, however, being slow to release, stays operated until the relay 70 is again operated during the next 35 impulse cycle. Further impulse cycles produced at the contacts of the dialing device cause alternate operation and restoration of the line relay 70, thereby repeating these impulses over the circuit of the trunk line 24 at the contact 72. Following the operation of the selector switches and the connector to select the called subscriber's line, the usual operations of applying ringing potential to the called subscriber's line, guarding the called line against seizure, and the like, are carried out in the conventional manner by means of 40 apparatus, not shown, and forming no part of the invention. Since the system as thus far described is entirely conventional it is believed that the restoration of the apparatus shown, following the termination of a call, will be apparent to those skilled in the art and for that reason a description thereof is unnecessary.

Referring now more particularly to Fig. 2 of the drawings, there is illustrated the circuit of Fig. 1 in diagrammatic form, with the circuit impedances of the subscriber's line 14 and the associated impedance elements shown in detail. Thus, the series resistance of the line is represented by the resistors 100 and 101; the shunt leakage resistance between the conductors 15 and 16 is indicated by the dotted line resistor 102; the capacitance between the line conductors 15 and 16 is shown by the dotted line capacitor 103; the impedance of the elements of substation 39 in series with the contacts of the impulsing device is indicated by the inductor 104; the impedances of all the ringer circuits of the line are indicated by the serially connected condenser 106 and inductor 105, and the windings of the line repeater 75 relay 70 are indicated at 107 and 108, respec-

tively. Other elements of the circuit are identified by the same reference characters as are used in the circuit of Fig. 1.

As was pointed out above, the faithfulness with which the line relay 70 responds to impulses received over the line 14 and occasioned by the operation of the impulsing device including the contacts 47 and 48, depends upon the relation between the rate of impulsing, the circuit constants of the line, and the impedance elements 10 associated therewith. Thus, with a normal impulsing rate within the range of from 8 to 12 interruptions per second and an extremely long line wherein the values of the resistors 100 and 101 are high, the current through the relay windings 107 and 108 may be insufficient to cause the relay 10 to operate. This problem is obviated by the use of the relay priming resistor 65 as noted above which effectively shunts, during the open circuit period of each impulse cycle when the relay 70 is restored, a sufficient amount of current from around the loop circuit so that when the contacts 47 and 48 are closed, the added current through the windings 107 and 108 causes positive operation of the relay.

It was further pointed out above that one form of impulse distortion which occurs in the impulse transmission path is caused by the voltage transient which occurs following the opening of the contacts of the impulsing device 49 at the end of 30 the closed contact period of each impulse cycle. This transient is caused by the rapid demagnetization of the relay 70 and functions to raise the line voltage between the conductors 15 and 16 to a value which may be several times the normal 35 line voltage. The polarity of this voltage transient is opposite that of the station battery but so greatly predominates thereover that the capacitors 106, 103, and 63, shunting the line are charged to a high potential. It is pointed out that 40 the distributed capacitance 103 of the line is of such a value as to have practically no effect on the magnitude or duration of the transient. The voltage transient in each impulse cycle reaches its peak at about the instant the relay 70 restores. 45 Following the charging interval, the capacitors 106, 103, and 63 discharge through the relay windings 107 and 108 and cause the relay to re-operate. Such spurious or false re-operation of the relay is somewhat momentary but if the series resistance 100, 101 is high, corresponding to a long line, the duration of the transient may be sufficient to cause re-operation of the distant control means which, in this case, comprises the line relay 50 53 of the connector switch 13. Such re-operation 55 of the relay 53 may result in the controlled vertical or rotary magnets taking two steps in each impulse cycle.

The above described phenomenon is, among other factors, dependent upon the value of the 60 shunt resistance of the line 14 including the leakage resistance 102 across the conductors 15 and 16 of the line circuit 14, and also upon the value of the combined capacitance of the capacitors 63 and 64. Thus, with the resistor 102 chosen to provide the greatest sensitivity of the relay 70 or of a value of approximately 2,000 ohms, a shunt leakage resistance of the order of 10,000 ohms to infinity, and the usual value of two microfarads for the voice-frequency by-pass capacitors 63 70 there is insufficient damping of the transient, with the result that the voltage transient as above described occurs and is of sufficient duration to cause false operation followed by a restoration of the line relay 70. The magnitude of this trans-

sient also depends upon the voltage of the common battery in the office 10 since the voltage across the windings of the relay 70 determines the rate of demagnetization thereof. Thus, if, in a given case, the voltage is reduced from 56 to 52 volts, false operation of the relay 70 may be entirely eliminated. With a low shunt leakage resistance between the line conductors, of the order of 5,000 to 10,000 ohms, the transient which occurs is sufficiently damped so that false operation of the relay 70 due to the cause described above is eliminated. Under these conditions, however, a second and equally undesirable transient results in each impulse cycle. This latter transient is caused by the opening of the circuit of the trunk line 24 at contact 72 when the line relay 70 restores in the usual manner. As this trunk circuit is opened, a current transient occurs in the secondary coils of the repeater transformer 56 which causes a voltage transient across the primary windings 57 and 58 of this transformer. This voltage transient aids the potential supplied by the battery through the priming resistor 65 to the winding 107 in the sense that it flows through the shunt leakage resistance 102 in series with the line resistance 100, 101, and thereby increasing the current through the windings 107 and 108 of relay 70. This added current causes a false re-operation of the line relay 70 which is repeated over the trunk conductors of the line 24. It is pointed out that, if the leakage resistance of the line is high, this second effect is prevented due to the discharging of the capacitors at about the time the transient caused by the opening of the trunk circuit occurs, since the polarities of the two transients are opposite. Under these conditions, however, the transient caused by the capacitor discharge is so greatly predominant that the transient produced by opening of the trunk circuit does not prevent the above described false operation of the line relay 70.

The exact nature of the impulse distortion which occurs is well illustrated in the graph of Fig. 3 which is an oscillographic record of the operation of a typical installation. This graph was taken on a system embodying a single repeater and having the following circuit constants for the elements of Fig. 2:

Resistance of resistor 65	ohms	2000
Combined resistance of resistors 100 and 101	ohms	0000
Resistance of resistor 102	ohms	5000
Series resistance of trunk line 24	ohms	750
Shunt resistance of trunk line 24	ohms	10000
Combined capacitance of capacitors 63 and 64	microfarads	6
Station battery voltage	volts	56
Impulsing rate	I. P. S.	8
No. substations on line 14		1

In this graph, the line A represents the current through the winding 108 of the line relay 70, the line B represents the current in the circuit of the trunk line 24, and the line C indicates the opened and closed periods of the back contacts of the line relay associated with the second selector switch 27. When this last-mentioned line relay is deenergized these back contacts are closed and vice versa. In the line A, the points D and E denote respectively the instant when the circuit of the subscriber's line 14 is interrupted at the contacts 47 and 48 and the instant when this line circuit is completed by these contacts during an impulsing operation and the distance D—D or E—E represents one complete impulsing cycle.

Points F and G of line B indicate the instants at which the current impulses in the circuit of the trunk line 24 produced by false operation of the relay 70 begin and end, and the distance between these lines indicates the duration of the transient causing such false operation. The points H and I indicate respectively the instants when the distant line relay of the second selector switch closes and opens its back contacts. It will be observed that, during each impulse cycle and shortly after the contacts at 47 open at the instants D, a current surge F—G occurs in the circuit of the trunk line 24 which causes a spurious or false operation of the distant relay at the second selector switch. Such false operation is probably the result of the transient caused by capacitor discharge, although the graph does not distinguish between the two causes as described above. As will be noted from the first impulse I—H of the line C, this false operation takes the form of a complete energization and re-operation of the relay 70 followed by a complete re-storing thereof. It is to be noted further that such false operations occur during each of the impulsing cycles. In the particular graph of this figure the false operation is of sufficient duration to cause the control device, which may comprise the vertical or rotary magnets of the selector switch, to take a false step in the manner pointed out above, thus resulting in improper trunk line selection.

As previously pointed out, the rate of impulsing is another factor which partially determines whether or not distortion in the form of false operation of the first repeater line relay will occur. This is strikingly emphasized by the graph of Fig. 4 which shows the operating characteristics of a system having the same characteristics as those for Fig. 3 with the exception that the combined capacitances of capacitors 63 and 64 were in this case 8 microfarads as contrasted with 6 microfarads for the system having the operating characteristics shown in Fig. 3. The same reference characters are used in Fig. 4 as in Fig. 3 to identify the same curves and the various points thereon. From Fig. 4 it will be observed that during the first impulse cycle and with an impulsing rate of exactly 8 interruptions per second no false operation of the relay 70 occurs. However, by the beginning of the second impulse cycle the impulsing rate had decreased to 7.7 I. P. S. with the result that a false operation of the relay 70 occurs. During the third impulse cycle the impulsing rate was still less with the result that the false operation of relay 70 was still more pronounced. From this graph it is apparent that, for a given set of system characteristics, the impulsing rate cannot be decreased below a predetermined value without causing the form of impulse distortion noted.

In accordance with the present invention, the distortion as described above, namely, spurious or false operation of the relay 70, is prevented or reduced to a tolerable value by including in the repeater 23 reactance means comprising the additional capacitance means 64 for delaying, during each impulse cycle, the occurrence of the transient for an interval after the contacts at 47 and 48 have opened to interrupt the circuit of the subscriber's line 14, and for increasing the duration of the transient sufficiently to permit the contacts at 47 and 48 to close and energize the relay 70 in the normal manner for the next impulse before the transient expires and the relay restores as a result of such expiration. This ad-

ditional capacitance means is connected in shunt with the voice-frequency by-pass capacitor 63 and the windings of the relay 70, and its purpose in the network is to increase the time constant of the network so that the current surge through the relay windings 107 and 108 is delayed in building up to a value sufficient to cause operation of the relay, and the duration of the surge is increased to hold the relay operated for a greater time interval which overlaps the instant of reclosure of the contacts at 47 and 48, initiating the next impulse cycle. Thus, referring again to Fig. 4, it will be seen that during the first half impulse cycle D—E, the transient as indicated by the current of the line 24 during the interval F—G overlaps the instant E when the contacts 47 and 48 are reclosed to initiate the next succeeding impulse cycle. Hence, when the transient is over and the relay 70 would normally tend to restore, it is held energized by virtue of the reclosure of its energizing circuit in the usual manner. It is pointed out here that the operating inertia of the relay 70 assists in increasing the operated time interval of the relay to make this interval overlap the reclosure instant E. In regard to the second impulse wherein the impulsive rate has decreased to 7.7 I. P. S. the transient occurs at the same instant in the impulse cycle as for the first half cycle but the delay in the reclosure instant E of the second impulse cycle caused by the decrease in impulsive rate permits the transient F—G to expire and the relay 70 to restore before the instant E arrives. Thus, false operation of the relay occurs during this and succeeding impulse cycles.

From the foregoing discussion with reference to Fig. 4, it will be apparent that for an impulsive rate above 8 interruptions per second and with the additional capacitance means 64 having a value of 8 microfarads, the latter element is so proportioned relative to the circuit constants of the line 14 and the constants of the other impedance elements associated with this line, including the elements of repeater 23, that the transient causing the false operation of the relay 70 holds the relay operated, during each impulse cycle, until the reclosure instant E occurs. It is pointed out that the circuit parameters given above for the system, upon which the operating characteristics of Fig. 4 are based, represent extremely unfavorable impulsive conditions and that any line having more favorable impulsive characteristics will operate perfectly satisfactorily in conjunction with the repeater as described above and having the present invention embodied therein. It is further pointed out that the shortening of the period representing the restored condition of the control means, due to the false operation of the relay 70, is not sufficient to have any adverse effect on the operation of the control means. In other words, the ratio of the restored period of the control means to the energized period of the control means is well within the range which permits complete operation and restoration of this means during each impulsive cycle.

In the system as described above impulse distortion in the form of false operation of the first repeater line relay is entirely eliminated by delaying, and increasing the duration of, the electrical transients causing false operation of the first impulse repeater line relay 70. If desired, and in those arrangements such as that illustrated wherein a number of repeaters are connected in tandem, at least a portion of the required delay may be supplied by the repeater line

relays of the repeaters following the first repeater 23. Each of these relays has a certain operating and restoring inertia such that a time interval elapses between energization and operation and between de-energization and restoration. The total operating interval representing the sum of the individual operating lags of the relays when added to the instant when false operation of the relay 70 occurs gives the instant when false energization of the distant control device occurs. Moreover, the interval corresponding to the combined restoring lags of these relays effects an increase in the interval during which the distant control means is falsely operated, thereby insuring that the false operation for each impulse cycle will continue well into the succeeding cycle. It was found that such operating and restoring lags caused a change in the ratio of the open-circuit period to the closed-circuit period for each impulse received at the distant control device from the ratio of these intervals as originally transmitted at the impulsive device, but not to an extent sufficient to cause undesired operation of the device ultimately to be controlled. This effect is well illustrated by the graph of Fig. 5 which is similar to those of Figs. 3 and 4 but shows the operating characteristics on a system including three repeaters connected in tandem over trunk lines. The characteristics of the system were as follows:

Operating voltage at all stations	volts	42
Impulsing rate	I. P. S.	12
Subscriber's line series resistance	ohms	0
Subscriber's line leakage shunt resistance	ohms	5,000
Series resistance of each trunk line	ohms	250
Leakage shunt resistance of each trunk line	ohms	10,000
Primings resistor 65 in first repeater	ohms	2,000
Capacitance shunting line relay windings of first repeater	microfarads	8
Substations on subscriber's line		6

In the graph the line A' represents the current through the negative winding of the first repeater line relay, the curve B' represents the current through the windings of the distant control device which in this case was the line relay 53 of the connector switch 37, and the curve C' represents the open and closed contact periods of the control device. The distance D'—E' indicates the open contact interval of the impulsive device 49 and the distance H'—I' indicates the corresponding interval during which the distant control device is de-energized. Likewise the distance E'—D' is a measure of the closed contact period of the impulsive means and the distance I'—H' is a measure of the corresponding interval during which the control device is energized. This graph strikingly illustrates the effect of the inertia of the relays in delaying the response of the control device. Thus, during the first impulse cycle, operation of the control device occurs almost at the end of the first half of the first impulse of the impulsive means as shown by the distance, along the time axis, between D' and H'.

It will be understood that if the impulsive conditions of the trunk lines, as for example the lines 24 and 29, interconnecting the various repeaters are particularly unfavorable it may be necessary to employ additional capacitance means in each of the repeaters in the manner described above for preventing false operation of the control

means at the distant office or station. In most instances, however, the trunk line characteristics are more favorable to impulse transmission than the subscribers' lines and consequently the expedient mentioned is unnecessary.

In practicing the invention as described above, the capacitor 63 and the additional capacitance means 64 may consist of two separate elements or they may be combined in the form of one capacitor having the appropriate capacitance value. In either case it has been found that if the total capacitance across the windings of the relay 70 is 8 microfarads, satisfactory operation is obtained when the repeater is operated in a system having the following characteristics:

Priming resistor 65	ohms	2,000
Series resistance of subscriber's line 14	ohms	0-1,250
Shunt leakage resistance of line 14	ohms— <u>infinite resistance</u>	5,000
Series resistance of each trunk line	ohms each	0-750
Shunt leakage resistance of each trunk line	ohms— <u>infinite resistance</u>	10,000
Impulsing rate	I. P. S.	8-12
Station battery voltage	volts	42-56
Number of substations on line 14		1-6
Number of trunk lines in tandem with line 14		1-3
Number of repeaters in tandem		1-3

The above parameters and physical characteristics of the system shown are given by way of example only since many other relationships between the various factors involved may be used without departing from the invention herein disclosed.

While there has been described what is at present considered to be the preferred embodiment of the invention it will be understood that various modifications may be made therein and it is aimed, therefore, to cover in the appended claims all such modifications as fall within the true spirit and scope of the invention.

45 I claim:

1. In a signaling system comprising a line, impulsing means on said line and a repeater adapted to be connected to said line to repeat electrical impulses received over said line to a second line and wherein the circuit constants of said line, the associated repeater and other apparatus associated with said line are necessarily so related as incidentally to produce false operation of said repeater following the interruption of the circuit of said line during an impulse cycle, the method of operation which includes, delaying said false operation for a time interval after the interruption of said line circuit, and starting the next impulse cycle by completing the circuit of said line before said interval expires.

2. In a signaling system comprising a line, impulsing means on said line and a repeater adapted to be connected to said line to repeat electrical impulses received over said line to a second line and wherein the circuit constants of said line, the associated repeater and other apparatus associated with said line are necessarily so related as incidentally to produce an electrical transient which causes false operation of said repeater following the interruption of the circuit of said line during an impulsing cycle, the method of operation which includes delaying the occurrence of said electrical transient for a time interval after the interruption of said line circuit, increasing the duration of said transient,

and starting the next impulse cycle before said transient expires by completing the circuit of said line.

3. In a signaling system comprising a line, impulsing means on said line and a repeater adapted to be connected to said line to repeat electrical impulses received over said line to additional repeaters adapted to be connected in with said first-named repeater over additional lines, and wherein the circuit constants of said line, the associated repeater and other apparatus associated with said line are necessarily so related as incidentally to produce false operation of said repeater following the interruption of the circuit of said line during an impulse cycle, which false operation is repeated by the other repeaters of the system, the method of operation which comprises, delaying said false operation of said repeater for a time interval after the interruption of said line circuit, delaying in said additional repeaters and for a further time interval the effect of said false operation on the last of said repeaters, and starting the next impulse cycle before the combined time intervals have expired.

4. In a signaling system comprising a line, impulsing means on said line and a repeater adapted to be connected to said line to repeat electrical impulses received over said line to additional repeaters adapted to be connected in tandem with said first-named repeater over additional lines, and wherein the circuit constants of said line, the associated repeaters and other apparatus associated with said line are necessarily so related as incidentally to produce electrical transients following the interruption of the circuit of said line during an impulsing cycle thereby to cause false operation of said first repeater, which false operation is repeated by the other repeater or repeaters, the method of operation which comprises delaying the occurrence of said transient for a time interval after the interruption of said line circuit, increasing the duration of said transient, delaying in said additional repeaters and for a further time interval the effect of the resulting false operation of the first-named repeater, and starting the next impulse cycle before the combined delay intervals have expired.

5. In a signaling system, a line, impulsing means for causing electrical impulses to be transmitted over said line, an impulse repeater adapted to be connected to said line and responsive to said impulses, said repeater being operative to repeat said impulses over a second line, said first-named line, impulsing means and repeater necessarily having included therein and associated therewith impedances which tend to produce false impulsing of said repeater, and reactance means associated with said repeater and so proportioned relative to said impedances as to prevent said false impulsing.

6. In a signaling system, a line, impulsing means for alternately closing and interrupting the circuit of said line at a predetermined rate to transmit electrical impulses thereover, an impulse repeater adapted to be connected to said line and including a relay energized when the circuit of said line is closed and de-energized when the circuit of said line is interrupted, said relay operating to repeat said impulses over a second line, means necessarily included in and associated with said first-named line for incidentally producing false energization of said relay during the time interval of each impulsing cycle when the circuit of said line is interrupted, and reactance means

associated with said relay for preventing, during each impulse cycle, the de-energization of said relay after its false energization.

7. In a signaling system, a line, impulsive means for alternately closing and interrupting the circuit of said line at a predetermined rate to transmit electrical impulses thereover, an impulse repeater adapted to be connected to said line and including a relay energized when the circuit of said line is closed and de-energized when the circuit of said line is interrupted, said relay operating to repeat said impulses over a second line, means necessarily included in and associated with said first-named line for incidentally producing, during the period of each impulse cycle when the circuit of said line is interrupted, an electrical transient which causes false energization of said relay, and reactance means associated with said relay for delaying, during each impulsive cycle, the occurrence of said transient following the interruption of the circuit of said line and for increasing the duration of said transient, whereby the circuit of said line is closed during any one cycle before the expiration of the transient of the preceding cycle.

8. In a signaling system, a line, impulsive means for alternately closing and interrupting the circuit of said line at a predetermined rate to transmit electrical impulses thereover, an impulse repeater adapted to be connected to said line and including a relay energized when the circuit of said line is closed and deenergized when the circuit of said line is interrupted, said repeater being operative to repeat said impulses over a second line, means necessarily included in and associated with said first-named line for incidentally producing, during the period of each impulse cycle when the circuit of said line is interrupted, an electrical transient which causes false energization of said relay, a resistor adapted to shunt the winding of said relay to increase the sensitivity thereof to received impulses and incidentally to increase the sensitivity of said relay to said transient, and capacitance means shunting said resistor for delaying, in each impulse cycle, the occurrence of the transient following the interruption of the circuit of said line and for increasing the duration of said transient, whereby the circuit of said line is closed during any one impulsive cycle before the expiration of the transient of the preceding impulsive cycle.

9. In a telephone system, a line, impulsive means on said line for transmitting electrical impulses thereover, an impulse repeater adapted to be connected to said line and including repeater windings for transmitting voice frequency currents over a second line, a relay included in said repeater having windings connected in series with a portion of said repeater windings, said relay being operative to repeat said impulses over said second line, the circuit constants of said first-named line, the elements of said repeater, and any other apparatus associated with said first-named line necessarily being so proportioned as incidentally to cause intolerable distortion of the repeated impulses, and capacitance means shunting the windings of said relay and so proportioned relative to said circuit constants that said distortion is reduced to a tolerable value.

10. In a telephone system, a line, impulsive means on said line for transmitting electrical impulses thereover, an impulse repeater adapted to be connected to said line and including windings for transmitting voice frequency currents

over a second line, a relay included in said repeater having windings connected in series with a portion of said repeater windings, said relay being operative to repeat said impulses over said second line, resistance means adapted to shunt the windings of said relay, the circuit constants of said first-named line, the elements of said repeater including said resistance means, and any other apparatus associated with said first-named line necessarily being so proportioned as incidentally to cause intolerable distortion of the repeated impulses, and capacitance means shunting the windings of said relay and so proportioned relative to said circuit constants that said distortion is reduced to a tolerable value.

11. In a telephone system, a line, impulsive means on said line for transmitting electrical impulses thereover, an impulse repeater adapted to be connected to said line and including repeater windings for transmitting voice frequency currents over a second line, a relay included in said repeater having windings connected in series with a portion of said repeater windings, said relay being operative to repeat said impulses over said second line, the circuit constants of said first-named line, the elements of said repeater, and any other apparatus associated with said first-named line necessarily being so proportioned as incidentally to cause false operation of said relay during each impulsive cycle, and capacitance means shunting the windings of said relay and so proportioned relative to said circuit constants that said false operation of said relay is prevented from causing false repeated impulses.

12. In a telephone system, a line, impulsive means on said line for transmitting electrical impulses thereover, an impulse repeater adapted to be connected to said line and including windings for transmitting voice frequency currents over a second line, a relay included in said repeater having repeater windings connected in series with a portion of said repeater windings, said relay being operative to repeat said impulses over said second line, a resistor adapted to shunt the windings of said relay, the circuit constants of said first-named line, the elements of said repeater including said resistor, and any other apparatus associated with said first-named line necessarily being so proportioned as incidentally to cause false operation of said relay during each impulsive cycle, and capacitance means shunting the windings of said relay and so proportioned relative to said circuit constants that said false operation of said relay is prevented from causing false repeated impulses.

13. In a telephone system, a line, impulsive means on said line for alternately closing and interrupting the circuit of said line to transmit electrical impulses thereover, an impulse repeater adapted to be connected to said line and including repeater windings for transmitting voice frequency currents over a second line, a relay included in said repeater having a winding connected in series with a portion of said repeater windings, said relay being energized when the circuit of said first-named line is closed and deenergized with the circuit of said first-named line is interrupted, and being operative to repeat said impulses over said second line, a resistor adapted to shunt the winding of said relay, the circuit constants of said first-named line, the elements of said repeater, and any apparatus associated with said first-named line being necessarily so proportioned as incidentally to cause

5 a voltage transient across said relay windings sufficient to cause false energization and operation of said relay during the period of each impulse cycle when the circuit of said line is interrupted, and capacitance means shunting said relay windings and so proportioned relative to said circuit constants that said voltage transient is delayed and the duration thereof is increased, whereby said relay is not de-energized
10 following the expiration of said transient.

14. In a signaling system, a line, impulsing means for transmitting electrical impulses over said line at a predetermined rate, an impulse repeater adapted to be connected to said line and including a relay for repeating said impulses over a second line, the circuit constants of said first-named line, the elements of said repeater and any apparatus associated with said first-named line necessarily being so related to each other
15 and to said predetermined rate of impulsing as incidentally to cause intolerable distortion of the repeated impulses, and reactance means connected in circuit with the windings of said relay and so proportioned relative to said circuit constants and said predetermined rate of impulsing that said distortion is reduced to a tolerable value.

15. In a signaling system, a line, impulsing means for transmitting electrical impulses over said line at a predetermined rate, an impulse repeater adapted to be connected to said line and including a relay for repeating said impulses over a second line, the circuit constants of said first-named line, the elements of said repeater, and any other apparatus associated with said first-named line being so related to each other and to said predetermined impulsing rate as incidentally to cause intolerable distortion of the repeated impulses, and capacitance means connected in shunt with the windings of said relay and so proportioned relative to said circuit constants and said predetermined rate of impulsing that said distortion is reduced to a tolerable value.

16. In a signaling system, a line, impulsing means for transmitting electrical impulses over said line, control means adapted to be controlled by said impulses, a plurality of impulse repeaters and at least one additional line adapted to be connected in tandem to inter-connect said line and said control means, the circuit constants of

said line, said additional lines, the elements of said repeaters and any other apparatus associated therewith being necessarily so related to each other as incidentally to cause intolerable distortion of the impulses received at said control means, and an impedance element associated with at least one of said repeaters and so proportioned relative to said circuit constants that said distortion is reduced to a tolerable value.

17. In a signaling system, a line, impulsing means for transmitting electrical impulses over said line at a predetermined rate, control means adapted to be controlled by said impulses, a plurality of impulse repeaters and additional lines adapted to be connected in tandem to inter-connect said line and said control means, the circuit constants of said line, said additional lines, the elements of said repeaters and of any other apparatus associated therewith being necessarily so related to each other and to said impulsing rate as incidentally to tend to cause false operation of said control means, and means comprising reactance means included in at least one of said repeaters for preventing false operation of said control means.

18. In a signaling system, a line, impulsing means for transmitting electrical impulses over said line, control means adapted to be controlled by said impulses, a plurality of impulse repeaters and additional lines adapted to be connected in tandem to inter-connect said line and said control means, each of said repeaters including a relay for alternately interrupting and closing the circuit of its associated line in response to said impulses, whereby said impulses are transmitted to said control means, the circuit constants of said line, the elements of said repeaters, said additional lines and other apparatus associated therewith necessarily being so related to each other as incidentally to cause intolerable distortion of the impulses received at said control means, the operating time interval of each of said relays being effective to reduce said distortion, and capacitance means included in at least one of said repeaters in shunt with the windings of the associated relay and so proportioned relative to said circuit constants that said distortion is further reduced to a tolerable value.
